UNITED STATES PATENT OFFICE.

JOHN G. EARHUFF AND RINALDO ALDEN, OF CHICAGO, ILLINOIS.

REED-ORGAN MUTE.

SPECIFICATION forming part of Letters Patent No. 326,551, dated September 22, 1885.

Application filed April 21, 1884. (No model.)

To all whom it may concern:

Be it known that we, JOHN G. EARHUFF and RINALDO ALDEN, both of the city of Chicago, county of Cook, and State of Illinois, have invented a new and useful Improvement 5 in Reed-Organs, of which the following is the specification, reference being had to the accompanying drawings, in which similar letters of reference indicate like parts in all 10 the figures.

Our invention relates to that part of a reed-organ which is known as the "mute," the object of which is to so regulate the admission of air to the reeds that they may be made to give 15 only a soft or subdued sound, which constitutes what is known to the art as the "soft stop."

In the drawings, Figure 1 represents a top view of the reed-board, showing the mute attached. Fig. 2 shows the front edge of the 20 same, and Fig. 3 shows a cross-section of the reed-board and the stop-action by which the mute is controlled.

In the figures, A is the sounding-board of 25 the organ, and placed thereon in the usual manner is the ordinary reed-board B, containing the reed-cells b. Covering the reed-cells b are the mutes C, which, for convenience, we will consider as being formed of a 30 single piece of wood, although in practice it is usually divided in the middle, as shown in the drawings.

C is the mute, and is hinged to the reed-board on its upper side (as shown in the drawings) by the hinges H. To allow the reeds to 35 sound, the mute C is turned on the hinges H, which movement raises the lower edge, x x, of the mute, as shown in Figs. 2 and 3, forming an aperture between it and the upper surface of the sounding-board, A, through which 40 the air enters to the reeds by the suction of the bellows.

Heretofore, in organs of usual construction, the mute has been so constructed that, for an 45 angular movement of the same in opening, the edge x x is raised equally throughout its entire length, admitting as great a quantity of air to the reeds at the treble end as at the bass end of the register. This arrangement is

objectionable, because the admission of an 50 amount of air sufficient to cause the bass notes to sound at all is sufficient to cause the treble notes to sound with their full power, and an evenly soft tone is not given by the reeds throughout the entire register. 55

To overcome this objection is the object of our invention, and we accomplish our object by so arranging and constructing the mute of our improved organ that the aperture for the admission of air to the reeds shall gradually 60 increase in width from the treble to the bass notes, whereby each note receives a quantity of air just sufficient to cause them all to sound with equal power.

Our invention consists in the new and improved construction and arrangement of the mute by which this result is secured.

In attaching the mute C to the reed-board B, we place the hinges H in the line z z, which deflects from the line of contact Y Y, 70 as shown in Fig. 1, between the mute C and the reed-board B. The line z z then becomes the axis of revolution of the mute C, and as the line z z, in deflecting from the line of contact S S, deflects also from the edge x x of the 75 mute C, the edge x x of the latter, when it is turned on the hinges H, will open wider at the left or bass end than at the right or treble end, and points between, on the edge x x, will be on a line between these extremities, as 80 shown in Fig. 2, and the aperture between the edge x x of the mute and the sounding-board A will gradually and continuously increase in width from the treble end to the bass end of the mute. 85

By this arrangement the admission of air to the reeds is so regulated that while only a small amount is admitted to the small reeds in the treble notes, and they are permitted to sound only softly, the amount of air admitted 90 to the successive reeds toward the bass end is gradually increased with each, as it requires more to cause it to sound, and all the reeds are thus made to sound with equal power throughout the entire register. 95

We are aware that mutes for reed-organs have been constructed heretofore, so that in opening the aperture between its edge and

the sounding-board has been greater at one end than at the other, and we do not claim that feature, broadly.

We claim—

- 5 In a reed-organ, the mute C, hinged to the reed-board B along the deflecting-line $z\ z$, whereby, for an angular movement of the mute, the aperture between the edge $x\ x$ thereof and the sounding-board A will be of continuously-increasing width from the treble

to the bass end of the mute, substantially as shown, and for the purposes described.

JOHN G. EARHUFF.

RINALDO ALDEN.
